REELING DEVICE

Calvin S. Roosa, West Englewood, N. J.

Application July 21, 1943, Serial No. 495,632

4 Claims. (Cl. 242—2)

This invention relates to a winder or reeling device of simple and practical construction and is especially adapted for winding yarn or similar materials on a core in substantially ball formation, and has for the primary object the provision of a device of this character which will be extremely easy to operate and will evenly and efficiently wind material obtained from a skein so that the possibility of entanglement and slippage of the material will be obviated and will arrange the wound material to freely unwind as need therefor may occur.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawing, in which

Figure 1 is a side elevation, partly in section, illustrating a winding device constructed in accordance with my invention.

Figure 2 is a sectional view taken on the line 2—2 of Figure 1.

Figure 3 is a sectional view taken on the line 3—3 of Figure 1.

Figure 4 is a sectional view taken on the line 4—4 of Figure 1.

Referring in detail to the drawing, the numeral 5 indicates a portable support including a panel-like body 6 and a handle 7 whereby a person may conveniently grasp and support the device for use.

The body 6 is provided with a bore in which is tightly fitted a sleeve 8, one end of which has integral therewith a cam 9 held in a fixed position with respect to the support and spaced a limited distance from one edge of the body 6. The sleeve also has fixed thereon a washer or collar 10 and secured thereto is a bracket 11 terminating in a yarn guide 12 of spiral formation, as clearly shown in Figure 1.

The sleeve is to have non-rotation with respect to the body 6 and the securing thereof in the body can be carried out in any well known manner. The sleeve rotatably supports an operating shaft 13, one end of which has removably secured thereto a crank handle 14 whereby the shaft may be manually rotated.

In operation, the operator grasps the handle 7 with one hand to arrange the support 5 horizontally with the crank handle 14 disposed lowermost so that it can be conveniently rotated by 55

the other hand of the operator. The upper end of the shaft 13 has secured thereto a bracket 15 including angularly disposed portions 16 and 17. Said portions 16 and 17 are arranged at substantially 60° angle to each other with the portion 16 secured to the shaft 13 for rotation therewith. The portion 17 of the bracket 15 has detachably secured thereto and adjacent its free end one end of a spindle 18. A set screw 19 threads into said end of the spindle.

Journaled on the spindle 18 is a sleeve 20 being retained on the latter for rotation by the portion 17 of the bracket 15 at one end of the spindle, while the opposite end is engaged by a removable set screw 21 threaded into the end of the spindle. The portion 17 of the bracket 15 when the handle 7 is grasped arranges the spindle 18 and sleeve 20 at an upwardly inclined angle to the axis of rotation of the shaft 13, bisecting the axis of rotation of the shaft 13 substantially intermediate the ends of the sleeve 20. Said sleeve 20 has formed thereon a key 22 to fit within grooves provided in the apertured end plate of a core 23. The core 23 may be readily slipped onto the sleeve 20 from the uppermost end of the latter with the key 22 fitting within the key slots or ways so that the core will rotate with the sleeve 20. It is to be understood that the core has a tight frictional fit with the sleeve so that it will not accidentally slip endwise of said sleeve during the use of the device and also to retain the core so that the axis of rotation of the shaft 13 extends to the core in a diagonal manner as indicated in Figure 1.

The guide 12 of the bracket 11 is arranged horizontally to the core so that the yarn will feed onto the core as indicated by the arrow in Figure 1.

Pivoted on the portion 16 of the bracket 15 by a pivot 16', is a lever 24, one end of which is bifurcated, as shown at 25, to engage with the cam 9 and the opposite end is bifurcated, as shown at 26, to receive a reduced end 27 of a lever 28 journaled on the set screw 19. The free end of the lever 28 is bent angularly, as shown at 29, to form a support for a spring type dog 30. A ratchet gear 31 is formed on one end of the sleeve 20 and is engaged by the dog 30. Pivoted on the portion 17 of the bracket 15 is a dog 32 also engageable with the ratchet gear 31. One end of the dog 32 is weighted to hold the dog in engagement with the ratchet gear. The purpose of the dog 32 is to restrain the ratchet gear against rotation when the dog 30 is ratcheting relative thereto.

Pivotal movement of the lever 24 is brought about by the fixed cam and the rotation of the bracket 15 by the crank handle 14. The lever 24 in turn causes the lever 28 to pivot and the dog 30 carried thereby cooperates with the ratchet gear to bring about a step by step rotation of the sleeve 20.

With the device set up for operation, as shown in Figure 1, the operator grasps the handle 7 arranging the support 5 horizontally or substantially so and rotates the crank handle 14. The bracket 15 being secured to the shaft 13 rotates therewith carrying the spindle 18 and sleeve 20 therewith. During the rotation of the bracket 15 as specified the lever 24 is caused to rock on its pivot by the cam 9 imparting a rocking motion to the lever 28 which through the dog 30 brings about rotation of the sleeve 20 on the spindle 18 in a step by step movement. Thus it will be seen that a very efficient and practical device of a portable nature has been provided whereby material taken from a skein can be efficiently wound on a core with slippage and entanglement of the material entirely obviated.

While I have shown and described the preferred embodiment of my invention, it will be understood that minor changes in construction, combination and arrangement of parts may be made without departing from the spirit and scope of the invention as claimed.

Having thus described my invention, what I claim is:

1. In a reeling device, a portable support, a shaft journaled in said support, means for the rotation of said shaft, a bracket secured to the shaft, a spindle secured to said bracket and supported thereby to cross axis of rotation of said shaft at an inclination to said shaft, a sleeve journaled on said spindle, a core removably secured to said sleeve for the winding of material thereon, and means for rotating said sleeve in a step by step movement about said spindle during the movement of the latter with the bracket about the axis of rotation of the shaft.

2. In a reeling device, a portable support, a shaft journaled in said support, means for rotating said shaft manually, a bracket secured to said shaft and including angularly related portions, a spindle secured to one of said portions and supported at an inclination and crossing the axis of rotation of said shaft, a sleeve journaled on

said spindle, a core removably secured to said sleeve with the axis of rotation of said shaft bisecting the core diagonally thereof, means for guiding material onto said core, and means for rotating said sleeve about said spindle in a step by step movement during the movement of the latter with the bracket about the axis of rotation of the shaft.

3. In a reeling device, a portable support, a shaft journaled in said support, means for rotating said shaft manually, a bracket secured to said shaft and including angularly related portions, a spindle secured to one of said portions and supported at an inclination and crossing the axis of rotation of said shaft, a sleeve journaled on said spindle, a core removably secured to said sleeve with the axis of rotation of said shaft bisecting the core diagonally thereof, means for guiding material onto said core, a cam fixed to said support, a lever pivoted on the bracket and having a bifurcated end engaging the cam, a second lever journaled on said bracket and connected with the first named lever, a spring type dog carried by the second lever, a ratchet gear formed on the sleeve and engaged by said dog, a pivoted gravity actuated dog carried by said bracket and engageable with the ratchet gear to prevent rotation thereof during the ratcheting of the first dog relative to the ratchet gear.

4. In a reeling device, a portable support including a panel body and a handle, a sleeve secured to the body, a shaft journaled in said sleeve, a cam formed on said sleeve, a bracket secured to the shaft and including angularly related portions, a spindle secured to one of said portions and supported thereby at an inclination crossing the axis of rotation of the shaft, a sleeve journaled on the spindle, a ratchet gear secured to said sleeve, a core removably secured to said sleeve on which material is to be wound, a lever pivoted to said bracket and engaging the cam, a second lever pivoted on the bracket and operated by the first named lever, a dog carried by the second lever and engaging the ratchet gear, a second dog pivoted on the bracket and engaging the ratchet gear, a bracket secured to said sleeve, and a coil type guide for the material carried by the second named bracket and arranged at right angles to the axis of rotation of the shaft and adjacent the core.

CALVIN S. ROOSA.
